[57] ABSTRACT

Bearing races are produced by grinding the inner and outer surfaces of an end portion of an elongated pipe of bearing steel to the shapes of the surfaces of a bearing race by inner and outer surface grinding wheels, and then severing the end portion from the pipe by a cutting edge provided by the outer surface grinding wheel. Another grinding wheel is provided for plane grinding the bearing race end surface which is formed by the cutting operation. Each of the grinding wheels may have rough and finish grinding parts for simultaneously finish and rough grinding said end portion and an adjacent portion, respectively, of the pipe.

METHOD AND APPARATUS FOR PRODUCING THE BEARING RACES

BACKGROUND OF THE INVENTION

1. Field of the Invention

The present invention relates to a method and apparatus for producing bearing races.

2. Description of the Prior Art

Heretofore, bearing races have been manufactured either by treating pipe materials or bar materials of bearing steel in various steps, such as cutting, quenching, tempering, and grinding, or by treating the materials by various processes, such as plastic working, cutting, quenching, tempering, and grinding. In either case, it has been necessary to include a separate cutting operation. In preparing production facilities for bearings, the largest part of the investment in equipment is spent for cutting equipment. In addition, space and housing are required for accommodating the cutting equipment and a number of operators are required for operating the equipment. Furthermore, because the cutting operation includes the steps of loading and unloading the materials from the cutting equipment, the total manufacturing time is long. Also, extra personnel are required for loading and unloading the cutting machine.

SUMMARY OF THE INVENTION

Accordingly, a principal object of the present invention is to provide a method and apparatus for manufacturing bearing races which reduces the heretofore high cost of equipment and personnel and shortens the manufacturing time.

In accordance with the invention, bearing races are formed from an elongated pipe of quenched and tempered bearing steel by a grinding machine which has formed-type grinding wheels for grinding the inner and outer surfaces of an end portion of the pipe to the shapes of the inner and outer surfaces of a bearing race. One of the grinding wheels is provided with a cutting edge for severing the end portion from the pipe after grinding is completed to produce a bearing race from the end portion, thereby eliminating the need for separate cutting equipment. An additional grinding wheel is provided for plane grinding the bearing race end surface which is formed by the cutting operation. Each of the grinding wheels may have rough and finish grinding parts for simultaneously finish and rough grinding said end portion and an adjacent portion, respectively, of the pipe.

BRIEF DESCRIPTION OF THE DRAWINGS

The invention will be further described with reference to the accompanying drawings, which illustrate a preferred and exemplary embodiment, and wherein:

FIG. 1 is a plan view of apparatus in accordance with the invention, but with some of the covers removed to assist understanding, this view showing a pipe mounted in the apparatus;

FIG. 2 is a right side elevational view of the apparatus of FIG. 1, but with an operating board omitted therefrom;

FIG. 3 is a transverse cross-sectional view taken approximately in the plane of line III—III of FIG. 1;

FIG. 4 is a longitudinal cross-sectional view of a pipe spindle employed in the apparatus of FIG. 1, this view

being taken approximately in the plane of line IV—IV of FIG. 1;

FIG. 5 is a longitudinal cross-sectional view of a grinding wheel and associated spindle employed in the apparatus of FIG. 1 for grinding the outer surface of an end portion of the pipe, this view being taken approximately in the plane of line V—V of FIG. 1;

FIG. 6 is a partial longitudinal cross-sectional view taken approximately in the plane of line VI—VI of FIG. 1, this view showing a grinding wheel and associated spindle for grinding the inner surface of an end portion of the pipe;

FIG. 7 is a transverse cross-sectional view taken approximately in the plane of line VII—VII of FIG. 1;

FIG. 8 is a longitudinal cross-sectional view of a front bar feeder mechanism employed in the apparatus of FIG. 1, this view being taken approximately in the plane of line VIII—VIII of FIG. 1;

FIG. 9 is a partial longitudinal cross-sectional view taken approximately in the plane of line IX—IX of FIG. 1, this view showing a grinding wheel and associated spindle for grinding the end surface of a bearing race;

FIG. 10 is a partial side elevational view showing the end of the pipe and the inner surface grinding wheel spindle broken away and in cross section to illustrate the inner surface grinding position of the apparatus of FIG. 1;

FIG. 11 is a partial transverse cross-sectional view taken through the end of the pipe for the inner surface grinding position of FIG. 10;

FIG. 12 is a partial transverse cross-sectional view taken approximately in the plane of line XII—XII of FIG. 10;

FIG. 13 is a side elevational view of a formed-type grinding wheel which may be employed in the system of FIG. 1 for grinding the outer surface of an end portion of the pipe;

FIG. 14 illustrates the operation of the grinding wheel of FIG. 13;

FIG. 15 is a side elevational view of another formed-type grinding wheel which may be employed in the apparatus of FIG. 1 for grinding the outer surface of an end portion of the pipe;

FIG. 16 illustrates the operation of the grinding wheel of FIG. 15;

FIG. 17 is a longitudinal cross-sectional view of a grinding wheel which may be employed in the apparatus of FIG. 1 for grinding the inner surface of an end portion of the pipe;

FIGS. 18—21 illustrate a method in accordance with the invention for manufacturing the outer race of a ball bearing;

FIGS. 22—25 illustrate a method in accordance with the invention for manufacturing the inner race of a ball bearing; and

FIG. 26 is a block diagram showing an electrical control circuit for operating the apparatus of FIG. 1 in a continuous manufacturing mode.

60 DESCRIPTION OF THE PREFERRED EMBODIMENTS

A preferred embodiment of a grinding machine in accordance with the invention will be described with reference to the accompanying drawings. In FIG. 1, the grinding machine is provided with pipe spindle means A, grinding wheel spindle means B for outer surface grinding, grinding wheel means C for inner surface

grinding, grinding wheel means D for plane grinding, front bar feeder means E, rear bar feeder means 75, and a power board 34. The spindle means A is secured to a bed 1 through a base 2. An elongated pipe 3 of quenched and tempered bearing steel to be worked is fed through an opening of said spindle and held and rotated by means of said spindle means A. This spindle means A has a construction as shown in FIG. 4 in which the spindle 4 is rotatably supported on a housing 5 by the front bearing means 6 and the rear bearing means 7, said housing 5 being secured to the bed 1 through said base 2. On the spindle, to a flange 8 located frontwards of the spindle 4 is secured a front power chuck 9, and on the rear end of the spindle 4 is secured a rear power chuck 10 to be rotated along with the spindle 4. Both front power chuck 9 and rear power chuck 10 are operated by oil pressure. The drawing shows the chucks in their open position. When the piston 11 is moved in the direction shown by the arrow, the conical inner surface of the piston 11 depresses the conical surfaces of pawls 12, which are mounted for radial movement in the chuck body 21, the movement of the pawls being limited by said chuck body 21 and a front cover 13, so that the steel pipe 3 (FIG. 1) is gripped by the pawls when they are moved in radial directions. When the piston 11 is moved in the direction opposite to said arrow, pawls 12 are returned to their original positions by springs (not shown) for releasing the steel pipe 3. A shell portion 14 of the rear power chuck is provided in its outer surface with a V-channel for receiving a V-belt. The V-belt connects the V-pulley of a motor (not shown) and the shell 14 through a belt hole 15 in the housing 5 to rotate the spindle 4. Fitted in the middle portion between the front bearing means 6 and the rear bearing means 7 of the spindle 4 is a bushing 16, which is secured to the housing 5 by means of bolts (not shown) projected from said housing 5. The bushing 16 is provided with two oil ports (not shown) and peripheral channels 17 and 18 each in communication with respective oil ports, one peripheral channel 17 being connected with an oil passage 19 in communication with a cylinder chamber on the side for opening the chuck, and the other peripheral channel 18 being connected with an oil passage 20 in communication with a cylinder chamber on the side for closing the chuck by moving the piston 11 in a direction shown by arrow. Said oil ports are connected to a change-over valve (not shown) and the chuck is opened and closed by operation of said change-over valve. A reference numeral 22 denotes a cover for the housing 5. With such a construction of the spindle means A, the operation of opening and closing the change-over valve instantaneously opens and closes the front and rear chucks 9 and 10 so that the steel pipe 3 may be supported and fed. The steel pipe 3 is firmly chucked at both the front and rear ends of the relatively long spindle 1 so that, if vibration occurs in the steel pipe itself, little vibration is produced in the middle portion between both chucks 9 and 10, and any vibration in the front working part of the front power chuck 9 caused by the vibration in the middle portion thereof is further reduced to promote working accuracy, thus providing a solid construction which can endure high speed rotation of lengthy steel pipe.

The grinding wheel spindle means B for outer surface grinding, as shown in FIG. 1 to FIG. 3, mainly comprises a grinding wheel spindle 25 formed integrally

with a slide base 24 which slides on the base 23 secured to the bed 1, a driving motor 27 mounted on the slide base 24 through a motor base 26b and a motor base slide 26a and connected with said grinding wheel spindle 25 by means of V-belts 28, outer surface dressing means including a grinding spindle 30 rotatably axially supporting a rotary diamond dresser 29 for outer surface grinding of an outer surface grinding wheel 33 and its motor 31, and a feed box 32 secured to the base 23 for feeding the slide base 24 relative to said spindle means A. The outer surface grinding wheel 33 is always in contact with the rotary diamond dresser 29. When some of the bearings are gound, a skip dress counter provided in the power board 34 is actuated to move a dress cut device 35 mounted on the right side of the motor base 26b so that the outer surface dressing means 29 is moved closer to the grinding spindle 25 together with a dresser base 36. At the same time, grinding wheel correcting means (not shown) provided in the base 23 is actuated to slightly feed the slide base 24 towards the spindle means A. The numeral 37 in FIGS. 2 and 3 designates a grinder cover. As shown in FIG. 5, the grinding wheel spindle 25 is provided near its axial end with the outer surface grinding wheel 33 for grinding the outer surface of the workpiece and further has fixed to the same end a rotary diamond dresser 39 for dressing an inner surface grinding wheel 38. That is, the diamond dresser 39 and the outer surface grinding wheel 33 have in common spindle 25, the motor 27 and the like so that the construction can be simplified to that extent.

The grinding wheel spindle means, which is provided with the inner surface grinding wheel 38 for grinding the inner surface of the hollow workpiece 3, has such construction that the inner surface grinding wheel 38 invades into the steel pipe 3 held by the spindle means A and fed therethrough for the grinding operation. As shown in FIGS. 1, 2 and 6, there is provided a slide base 41 which is slidable on a base 40 mounted on the bed 1 in a direction at a right angle to the axis of said spindle means A, said slide base 41 being made slidable by means of a feed box 42 and a feeding mechanism controlled thereby. Secured to the slide base 41 is a spindle base 45, which is provided thereon with a spindle slide head 44 to be reciprocated in a direction parallel to the axis of said spindle means A (i.e., parallel to the longitudinal axis of pipe 3) by means of an inner surface grinding wheel indexing power-cylinder 46 secured to the spindle base 45, and a grinding wheel spindle 43 carrying the grinding wheel 38 is secured to said spindle slide base 44. The grinding wheel spindle 43, as shown in FIGS. 10 to 13, is provided with a front cover 102, which seals its front portion and facing grinding wheel 38. The front cover is formed with an annular space 103 therein. This annular space is formed by cutting a peripheral channel in the inner surface of said front cover 102 and fitting a bushing 104 therein under pressure. There are provided several injection ports 105 opening into the front of the front cover and connecting said annular space with the front of the front cover. A liquid entrance passage 106 is communicated with said annular space 103, and a pipe joint 107 is connected therewith so as to introduce a high pressure grinding liquid into the space 103. The grinding liquid is injected immediately in front of the grinding wheel 38 from the injection ports 105. By properly selecting the diameter of the grinding wheel and the position of

the injection ports 105, the grinding liquid is caused to adhere to the inner surface of the steel pipe 3 during inner surface grinding without rebounding on the side of grinding wheel and without striking against the grinding wheel diagonally, so that grinding efficiency may be promoted and the grinding liquid may effectively be used during the high speed grinding operation. The power-cylinder 46 is, as shown in FIG. 6, of a double cylinder type, and the position shown in the drawing indicates the dressing position of inner surface grinding wheel 38, and the position in which piston 47 is in contact with the front cover 49 of the inner cylinder 48 corresponds to the grinding position wherein the grinding wheel 38 invades into the steel pipe 3. In the position in which the inner cylinder 48 is in contact with rear cover 51 of the outer cylinder with the piston 47 being maintained in contact with the rear cover 50 of the inner cylinder 48, the grinding wheel 38 can be replaced by means of automatic grinding wheel exchanges 52a and 52b. In FIG. 7, a power cylinder 53 for the dressing operation is secured to the lower surface of the slide base 41, and the piston rod thereof is made integrally with the piston rod of a power cylinder 54 for reciprocating the slide base. This power cylinder 54 is integrally formed with a housing part 55 which is slideable on the inner surface base 40. A nut 56 of a feed screw mechanism is fixed in an axial direction to said housing part 55, and the rotation of a feed screw 57, controlled by the feed box 42, is changed into a rectilinear motion of the slide base 41 through said two power cylinders 53 and 54. The front bar feeder means E, which is provided with a rotary shaft parallel to the inner surface grinding wheel spindle 43, is slidably mounted on the slide base 41. That is, a feeder base 61 is secured to the slide base 41, a feeder slide base 62 is adapted to be reciprocated on the feeder base 61 by means of a first power cylinder 59 for feeding, and a feeder body 63 is adapted to be reciprocated on the feeder slide base 62 by means of a second power cylinder 64 for feeding. A motor 65 is secured to the feeder body 63 to rotate a feeder shaft 66 rotatably supported in the feeder body or spindle 63, the shaft being rotatable about an axis parallel to the longitudinal axis of the pipe 3. The first and second feeder power cylinders 59 and 64 are secured at right angles to each other to the feeder slide base 62, and the end of the rod of the piston 60 in the first feeder power cylinder is connected to an arm 58 secured to the inner surface base 40. The stroke of the first power cylinder 59 is the same as the maximum stroke of the power cylinder 54 for reciprocating the slide base and coincides with a reciprocating stroke of the front bar feeder means E, as hereinafter described, in a direction perpendicular to the axis of the spindle 4. Oil is simultaneously fed under pressure by the same change-over valve to said two power cylinders 54 and 59 which have same stroke as described above. In FIG. 7, when the first feeder power cylinder 59 moves leftwards relative to the piston 60, the piston 67 of the power cylinder 54 for reciprocating the slide base will move leftwards relative to the cylinder 54 and the inner surface slide base 41 will move leftwards. A stroke control device 68 is secured to the right end of the power cylinder 54. When the grinding wheel 33 is dressed as previously described and the grinding wheel spindle 25 comes near the spindle means A, a gear 69 of said stroke control device is rotated by a pulse motor (not shown) to rotate a screw 70. A shaft 71 and a

sleeve 72 fitted therearound are moved leftwards by the same amount as the amount which said grinding wheel spindle 25 has moved, so as to shorten the stroke. Thereby, the clearance *a* between the inner surface grinding wheel 38 and the inner surface grinding rotary dresser 39 mounted at the utmost end of the outer grinding wheel spindle 25 can be maintained constant. The stroke length *b* of the dressing power cylinder 53 is made slightly greater than said clearance *a* so as to dress the inner surface grinding wheel 38. When the stroke of said slide base reciprocating power cylinder 54 is decreased, the axial center of the feeder shaft 66 is displaced sideways to provide a clearance equal to the amount of decrease in stroke between the piston 60 of the first feeder power cylinder 59 and the rear cover 73. However, the feeder slide base 62 is moved rightwards by the amount of said clearance by means of the first power cylinder 59 alone to avoid the deviation of the axial center of feeder shaft 66. This feeder shaft 66 is, as shown in FIG. 8, provided near the front end of the spindle means A with a magnetic chuck 74. A nosepiece 76 is mounted on the magnetic chuck and adapted to be attracted to the end surface of steel pipe 3 which is held and rotated by the spindle means A. The position of the chuck, that is, the position of the center of shaft 66, is such that the position in which the axial center coincides with the axis of the spindle 4 is made the reference or zero position in a path perpendicular to the axis of the spindle 4, and the terminal position of the path is a position in which the end surface of a bearing race held in the magnetic chuck is surface-ground by means of the grinding wheel spindle means D for surface grinding, hereinafter described. This zero position may be secured by reciprocating motion of the first feeder power cylinder 59, even if the return of the inner surface slide base is varied as described above. The second feeder power cylinder 64 is provided to effect reciprocating motion of the front bar feeder means 40 in an axial direction of the spindle means A (i.e., parallel to the longitudinal axis of pipe 3). The second feeder power cylinder 64 is secured to the feeder slide base 62 and comprises a front cylinder 80 and a rear cylinder 81, as shown in FIG. 8. The rod of piston 79 of the front cylinder 80 is secured to a member 77 which projects from the lower surface of the feeder body 63 so that the feeder body or chuck spindle 63 may be moved in an axial direction by moving the piston 79 through the front cylinder 80. The rod of piston 85 of the rear cylinder 81 extends into the front cylinder 80, passing through a partition wall 84 which separates the front cylinder 80 from the rear cylinder 81, to limit the stroke of piston 79 of the front cylinder. The front bar feeder means E pulls the steel pipe 3 out of the spindle means A by reciprocating motion of the second feeder power cylinder 64 and after the outer surface grinding wheel spindle means B has completed cutting the ground end portion from the pipe to produce a bearing race (as described in detail later), the feeder means E transports the bearing race by means of the first feeder power cylinder 59 towards the grinding wheel spindle means D for plane grinding the bearing race end surface which is formed by cutting the end portion from the pipe to produce that bearing race. Furthermore, the piston 85 of the rear cylinder 81 is moved into contact with the rear cover 86 so that the stroke of piston 79 of the front cylinder may be in-

creased to thereafter discharge the bearing race held in the spindle means.

Referring to FIG. 1, the grinding wheel spindle means D for plane grinding has the axis of its grinding wheel shaft perpendicular to the axis of the spindle means A, and is fed for the grinding operation on the bed 1 at a right angle relative to the axis of the grinding wheel, that is, in a direction parallel to the axis of the spindle means A. The surface grinding wheel spindle 89 is of the type having a built-in motor, and a surface grinding wheel 90 is of a flat type and is formed by a dressing device 91 mounted on the front bar feeder means E. In FIG. 9, a plane base 93 is secured to the bed 1, and a plane slide base 94 is adapted to be slidable on the plane base 93. The grinding wheel spindle 89 for plane grinding and a plane feed box 92 are provided on said plane slide base 94. The rotation of the plane feed box 92 is transmitted to a feed screw 97 through bevel gears 95 and 96, and a nut 98 for the feed screw is mounted in bearing 100 in a housing 99 secured to the plane base 93. The slide base 94 is slided to effect inching feed and correction with respect to the grinding wheel spindle 89 for plane grinding. The numeral 75 in FIG. 1 denotes material feeding means and has a mechanism for initially feeding the steel pipe 3 into the spindle 4 of spindle means A until the pipe reaches the nosepiece 76 of the feeder shaft 66, which is in the forwardmost position.

The outer surface grinding wheel 33 and the inner surface grinding wheel 38 shown in FIGS. 13 to 17 will now be described. These grinding wheels are formed-type grinding wheels formed by means of rotary diamond dressers. The outer surface grinding wheel 33 for producing a bearing outer race comprises a grinding wheel part 33A for rough grinding, a grinding wheel part 33B for finish grinding, and a cutting part 33C. The cutting part 33C is located at the side of the grinding wheel part 33B apart from the grinding wheel part 33A and is extended from a chamfer grinding part perpendicularly relative to the axis of grinding wheel. There is shown in the drawing a grinding wheel provided with the grinding wheel part 33A for rough grinding and the grinding wheel part 33B for finish grinding, but an intermediate finish grinding wheel part may also be employed therebetween. The chamfer grinding part is perpendicularly projected from the cylindrical portion of the grinding wheel part 33B, and a corner portion of said cylindrical portion is formed to have an axially curvilinear surface to grind the chamfer. The dimension and shape of the grinding wheel part 33A and the grinding wheel part 33B are determined according to dimension and shape of the whole outer peripheral surface of the bearing outer race and the rough and finish grinding areas. When the grinding area is large, a grinding wheel part for intermediate-finish grinding provided between the grinding wheel part 33A and the grinding wheel part 33B. The chamfer grinding part includes the cutting part 33C, a central chamfering part 33D between the grinding wheel part 33B and the grinding wheel part 33A, and a rough chamfering part 33E located on the other side of grinding wheel part 33A. The size of chamfering and depth of cut into the outer peripheral surface of steel pipe 3 are greater at the central chamfering part 33D than at rough chamfering part 33E. However, it is so designed as to have same width between the three parts 33C, 33D, and 33E. The diameter 33a of the cylindrical part of the

grinding wheel part 33A is smaller by the finish grinding thickness than the diameter 33b of the cylindrical part of the grinding wheel part 33B. The diameter of the cutting part 33C is determined so that the time for dressing of the cutting part 33C may coincide with other parts, considering the of thickness of steel pipe 3 to be cut, said chamfering parts 33D and 33E, diameters 33a and 33b of the cylindrical parts, and the like. FIGS. 15 and 16 illustrate an embodiment of a grinding wheel 33' for grinding the outer periphery of the inner race of a ball bearing, which comprises a grinding wheel part 33A' for rough grinding, a grinding wheel part 33B' for finish grinding, and a cutting part 33C' in the same manner as grinding wheel 33. The shape of outer peripheral surface of the inner race includes a track channel and a seal surface so that it is more complicated than that of the outer race. The diameter of each part may be determined in the same manner as for grinding wheel 33. The width of rough chamfering part 33E' is made to be wider than that of central chamfering part 33D' and cutting part 33C'. However, the dimensions between the three parts 33C', 33D' and 33E' are equal each other, as in the case of grinding wheel 33. FIG. 17 shows a grinding wheel 38 for grinding of inner surface of an outer race of a ball bearing, which comprises a grinding wheel parts 38A for rough grinding and a grinding wheel part 38B for finish grinding. The dimensions and shape of said grinding wheel 38 are determined in a manner similar to those of outer surface grinding wheel 33. The outer surface and inner surface appearing in this embodiment of the invention indicate all surfaces and chamfers, including projections, hollows and the like present in the outer surface or inner surface. When the steel pipe is cut and ground by maintaining the rotary axis of grinding wheel parallel to the rotary axis of steel pipe 3 while using the grinding wheels as described above, end portions 3a and 3a' of the steel pipe at the right hand of cutting parts 33C, and 33C' shown in FIGS. 14 and 16, are severed to form bearing race units. Simultaneously, end portions 3b and 3b' adjacent portions 3a and 3a' contact finish grinding wheel parts 33B and 33B' to be finish-ground, and at this time one side surface of the bearing race to be ground (the outer end of portions 36 and 36') is finished perpendicularly relative to the axis of the bearing race by cutting parts 33C and 33C'. Furthermore, end portions 3c and 3c' of the steel pipe adjacent portions 3b and 3b' simultaneously are ground by rough grinding parts 33A and 33A'. Thus, when the steel pipe 3 is successively fed in amounts corresponding to the length of one piece of product plus a cutting area, each of the end portions of said steel pipe 3 is successively rough ground, finish-ground, and severed to obtain bearing race units. This process of manufacture will be described in detail by taking as an example, the bearing outer race shown in FIGS. 18 to 21. An elongated steel pipe 3 of quenched and tempered bearing steel is fed so that a length suitable for two bearing outer races to be ground passes through the spindle. At this time, the nosepiece 76 on the front bar feeder means E waits as a stop for the steel pipe at the position shown in FIG. 18, and when the steel pipe 3 is chucked by the spindle means, the front bar feeder means retreats. Then, the outer surface grinding wheel spindle means B is moved toward the pipe along an axis perpendicular to the longitudinal axis of the pipe so that the outer surface grinding wheel 33 is fed perpendicu-

larly to the outer surface for cutting into that surface. During this grinding operation, the inner surface grinding wheel spindle means C is moved along an axis parallel to the longitudinal axis of the pipe so that inner surface grinding wheel 38 enters the end of the steel pipe 3. After outer surface grinding has been completed, spindle means C is moved along an axis perpendicular to the longitudinal axis of the pipe for feeding grinding wheel 38 perpendicularly to the inner surface of the pipe for its grinding operation. During the operation of inner surface grinding, the outer surface grinding wheel 33, which has completed its outer surface grinding, retreats and only inner surface grinding takes place, as shown in FIG. 19. Before long, the inner surface grinding is finished and the inner surface grinding wheel 38 retreats and moves out of the steel pipe 3, returning to the position as shown in FIG. 1. After this process has been completed, the end portion 3a at the utmost end of the steel pipe has been finish ground including its inner and outer surfaces and the planar end surface at the utmost end, and the adjacent portion 3b has its inner and outer surfaces rough ground. At this time, the front bar feeder means is positioned on the inner surface slide base 41 together with the inner surface grinding wheel spindle 43. When the feeder means thereafter returns to its zero point, the nosepiece 76 is moved forward to contact with said part 3a at the utmost end. Then, chucks 10 and 11 of the spindle 4 are opened and the nosepiece 76 is magnetized. Thereafter, the steel pipe 3 is pulled out in the direction of its longitudinal axis to the position shown in FIG. 20, where the front bar feeder means E is shifted so that the piston 79 may be in contact with the rod of the piston 85. Then, when said chucks 10 and 11 are closed to effect rotation of the pipe 3, said nosepiece 76 is rotated with the steel pipe 3. Then, said steel pipe 3 is ground by the outer surface grinding wheel 33, and end portion 3a which has its inner and outer surfaces already finish ground, is severed from the steel pipe 3 by means of cutting part 33c of the outer surface grinding wheel to produce a bearing outer race which is attached to the nosepiece 76, and then said nosepiece 76 is finally rotated by its own motor 65. The outer peripheral surface of rough-ground portion 3b is then finish-ground, and the outer surface of end portion 3c, just pulled out from the spindle A, is rough-ground. After this process has been completed, finish grinding of the outer surface of end portion 3b at the utmost end and rough grinding of the inner surface are completed. Rough grinding of the outer surface of the adjacent end portion 3c is completed, while its inner surface remains blank. Thus, to produce a bearing race, an end portion of the pipe is successively rough ground by the rough grinding part of the outer surface grinding wheel, rough ground by the rough grinding part of the inner surface grinding wheel, finish ground by the finish grinding part of the outer surface grinding wheel, finish ground by the finish grinding part of the inner surface grinding wheel, and then severed from the pipe by the cutting part of the outer surface grinding wheel. Thereafter, the steps shown in FIGS. 19 and 20 are repeated, so that a portion at the utmost end of the pipe is finish-ground, a frontwardly adjacent portion is rough-ground, and the portion already finish-ground is severed and transported to the grinding wheel spindle means B for plane grinding while being attracted to the nosepiece 76 of the front bar feeder means. The bearing race end sur-

face formed by cutting the end portion from the pipe, as shown in FIG. 21, is plane ground and then disengaged from the front bar feeder means E to be taken out thereof, thus continuously producing bearing outer races. In the case of ball bearing inner races, the steps shown in FIGS. 22 to 25 are repeated. If the bearing race is varied in its dimension and shape, an outer surface grinding wheel 33 and an inner surface grinding wheel 38 suited thereto are formed for use by appropriately shaped rotary diamond dressers 29 and 39. FIG. 26 is a block diagram of an electrical circuit for operating the machine in the continuous manufacturing cycle shown in FIGS. 19 to 21. In the block diagram, FF is a memory element; AND is an "and" circuit; NOT is a "not" circuit; and OR is an "or" circuit. With respect to the stopped position of the machine, the grinding wheel spindles for the outer surface, the inner surface and the end surface are in their retreated positions; the front bar feeder means is also in its retreated position; the dressing means is also stopped; FF1, FF2, FF3 and FF4 are reset; outputs TG2, ST, GIST and GE are all "0"; SoLT1 is actuated; and the main spindle is ready for the grinding operation, supporting the steel pipe in the grinding position. By actuation of a cycle start push button PBST, FF1 is reversed to the set state and output ST changes to "1." The inner surface slide base 41 is in its retreated position and limit switch signals LST1 and LST4 are "1", therefore the output of AND 7 is 1 and the output GE of FF4 is 0 so that GE through NOT 1 is 1 and the output of AND 1 is 1 and FF2 is reversed to the set state and G1ST is 1. Because G1ST is 1, MgCH is 1 through OR 1 and the magnetic chuck 74 of the front bar feeder means is actuated, WM is 1 and a motor of the spindle means is run to send the G1 grinding cycle unit a signal 1 and the grinding wheel spindle means B for outer surface grinding is actuated to start outer surface grinding. When cutting by the outer surface grinding wheel 33 is completed, the TS signal is turned to 1 and the output of AND 2 is 1, FF3 is reversed to the set state and the output TG2 is 1. Thereby, SoLT2 is turned to 1 and SoLT1 is 0 so that a solenoid valve for actuating the inner surface slide base is changed-over and the inner surface slide base 41 is moved to the position for inner surface grinding. At this time, the bearing race severed in the operation of outer surface grinding is moved to the position for plane grinding, being held by magnetic chuck 74. Meanwhile, the G1 grinding cycle unit continues the cycle of rough grinding. The inner surface slide base 41 is moved to the position for inner surface grinding, causing the limit switch signal LST2 to be 1, and the front bar feeder means E is also moved to the position of plane grinding, causing the limit switch signal LST3 to be 1. Thus output G2ST of AND 3 is changed to 1 to send signal 1 to G2 grinding cycle unit and G3 grinding cycle unit so that inner surface grinding and plane grinding operations are started. When the outer surface grinding cycle is completed, G1E is turned to 1; when the inner surface grinding cycle is completed, G2E is 1; and when the plane grinding cycle is completed, G3E is 1. Each grinding cycle herein mentioned indicates a series of grinding processes including a quick feeding, a rough finishing, a finishing, a spark out, a rapid return, and the like. Since G1E, G2E and G3E are turned to 1, the output of AND 4 is 1, FF4 is reversed to the set state and output GE is 1. Therefore, FF2 and FF3 are re-

versed to the reset state, G1ST and TG2 are 0 and G2ST from AND 3 is also 0, the grinding cycle units G1, G2 and G3 are reset and grinding completion signal G1E, G2E and G3E are also 0. Since G1ST is 0, MgCH is 0, then magnetic chuck 74 is OFF and the bearing race already processed and held by the front bar feeder means E is discharged. WM is also 0 to stop the spindle motor. On the other hand, G2 is 0, and SoLT2 is 0 and SoLT1 is 1, so that the inner surface slide base 41 is returned to its original position and the 5 chuck of front bar feeder means E is also returned to the zero position opposite the spindle means A. Consequently, LsT1 and LsT4 are changed to 1, and the input of AND 7 is 1 and GE is 1 as described above; therefore, output D2ST of AND 5 is also 1. If inner surface 10 grinding is not taking place, DS2 is 0 so that an input of AND 6 is 1 and the output BFST is 1 to start operating the bar feeder cycle unit. Therefore, BFMg is turned to 1 and MgCH through OR1 is 1 to actuate the magnetic chuck 74, and the bar feeder cycle is completed and BFE is 1. FF4 is reversed to the reset state and the cycle of operation of the machine is completed. When the cycle stop button PBST is placed in ON position and FF1 is reversed to the reset state, the machine will stop at the end of the cycle. If it is not set to ON position, the above cycle is repeated.

A bearing race manufactured in the foregoing manner is applied with superfinishing of its track face in a known manner, and thereafter said race forms part of a finished bearing having a combination of inner and outer races, rolling members and a cage. If a high degree of accuracy is required, the track face may be reground. Where the intended use of the bearing permits, the bearing can be constructed without superfinishing the track face.

According to the methods and apparatus thereof of the present invention, bearing races having all their surfaces ground can be continuously manufactured from an elongated steel pipe without prior processes, thereby eliminating the need for cutting or turning equipment. Furthermore, construction of the manufacturing apparatus is designed to provide high speed grinding so that actual grinding hours can be reduced less than the total hours required by prior art methods in which turning and grinding are divided into separate operations, whereby operating hours, the cost of turning equipment, and personnel expenses are reduced. Still further, since a bearing race is manufactured in the process of the invention from blank to finish grinding by one machine, it is not necessary to move the bearing races during the process so that process management is simple and extra labors for transportation, etc. may be saved. Furthermore, because the blank is held without being re-chucked by the spindle means for grinding of both the inner and outer surfaces, there is produced a bearing race having little one-sided thickness, good parallelism between both planes, and high dimensional accuracy. Still further, the steel pipe is pulled out front-wardly by means of front bar feeder means so that the length of steel pipe remaining in the spindle means may be shortened considerably for providing economical use of the material.

What I claim is:

1. A method for producing bearing races, the method comprising:
providing an elongated pipe formed of bearing steel;

grinding the inner and outer surfaces of an end portion of the pipe to the shapes of the inner and outer surfaces, respectively, of a bearing race; and then severing said end portion from the pipe to produce a bearing race therefrom, said grinding comprising finish and rough grinding the outer surfaces of said end portion and an adjacent portion, respectively, of said pipe by finish and rough grinding parts, respectively, of an outer surface grinding wheel, and finish and rough grinding the inner surfaces of said end portion and said adjacent portion, respectively, of said pipe by finish and rough grinding parts, respectively, of an inner surface grinding wheel.

2. A method according to claim 1, wherein said 15 grinding of the inner and outer surfaces of the end portion of the pipe is effected by inner and outer surface grinding wheels, respectively, and wherein said severing is effected by cutting means provided by one of said grinding wheels.

3. A method according to claim 1, further comprising 20 plane grinding the bearing race end surface which is formed by severing said end portion from the pipe to produce said bearing race.

4. A method according to claim 1, wherein said inner 25 and outer surface grinding wheels are formed-type grinding wheels, and wherein the method further comprises dressing the grinding wheels.

5. A method according to claim 1, wherein said end 30 portion is severed from the pipe by cutting means provided by one of the grinding wheels after said end portion has been rough and finish ground by the rough and finish grinding parts of the grinding wheels.

6. A method according to claim 5, wherein the cutting means is provided by the outer surface grinding wheel, and wherein said bearing race is formed from 35 said end portion of said pipe by the successive steps of rough grinding the outer surface of said end portion of the pipe with the rough grinding part of the outer surface grinding wheel, rough grinding the inner surface of said end portion with the rough grinding part of the inner surface grinding wheel, finish grinding the outer surface of said end portion with the finish grinding part of the outer surface grinding wheel, finish grinding the inner surface of said end portion with the finish grinding part of the inner surface grinding wheel, and cutting 45 said end portion from the end of said pipe by said cutting means.

7. A method according to claim 5, further comprising 50 plane grinding the bearing race end surface which is formed by cutting said end portion from the pipe to produce said bearing race.

8. Apparatus for producing bearing races from an elongated pipe of bearing steel, the apparatus comprising:

55 a pipe spindle for supporting the pipe for rotation about its longitudinal axis;
inner and outer surface grinding wheels for grinding the inner and outer surfaces, respectively, of an end portion of the pipe to the shapes of the inner and outer surfaces, respectively, of a bearing race; cutting means provided by one of the grinding wheels for severing the end portion from the pipe to produce a bearing race therefrom; and
60 a magnetic chuck supported for rotation about an axis parallel to the longitudinal axis of the pipe by chuck spindle means, wherein the inner and outer surface grinding wheels are supported for rotation

about axes substantially parallel to said longitudinal axis by inner and outer surface grinding wheel spindles, respectively, the inner surface grinding wheel spindle being movable along an axis substantially parallel to said longitudinal axis for enabling the inner surface grinding wheel to enter the end portion of said pipe and also being movable in a direction substantially perpendicular to said longitudinal axis for permitting the inner surface grinding wheel to be fed to the inner surface of said end portion, and the outer surface grinding wheel spindle being movable in a direction substantially perpendicular to said longitudinal axis for enabling the outer surface grinding wheel to be fed to the outer surface of said end portion, wherein the chuck spindle means is movable along said longitudinal axis for pulling the pipe a predetermined distance through said pipe spindle after the end portion has been severed from the pipe, and wherein the pipe spindle has power chucks at both ends for gripping the pipe and has means for causing the power chucks to release the pipe to enable the magnetic chuck to pull the pipe through the pipe spindle.

9. Apparatus for producing bearing races from an elongated pipe of bearing steel, the apparatus comprising:

a pipe spindle for supporting the pipe for rotation about its longitudinal axis;
inner and outer surface grinding wheels for grinding the inner and outer surfaces, respectively, of an end portion of the pipe to the shapes of the inner and outer surfaces, respectively, of a bearing race;
cutting means provided by one of the grinding wheels for severing the end portion from the pipe to produce a bearing race therefrom;

chuck means supported for rotation about an axis parallel to the longitudinal axis of the pipe by chuck spindle means; and

a plane grinding wheel for grinding the bearing race end surface which is formed by cutting said end portion from the pipe to produce said bearing race, the plane grinding wheel being supported for rotation about an axis substantially perpendicular to said longitudinal axis by a plane grinding wheel spindle, wherein the inner and outer surface grinding wheels are supported for rotation about axes substantially parallel to said longitudinal axis by inner and outer surface grinding wheel spindles, respectively, the inner surface grinding wheel spindle being movable along an axis substantially parallel to said longitudinal axis for enabling the inner surface grinding wheel to enter the end portion of said pipe and also being movable in a direction substantially perpendicular to said longitudinal axis for permitting the inner surface grinding wheel to be fed to the inner surface of said end portion, and the outer surface grinding wheel spindle being movable in a direction substantially perpendicular to said longitudinal axis for enabling the outer surface grinding wheel to be fed to the outer surface of said end portion, wherein the chuck spindle means is movable along said longitudinal axis for pulling the pipe a predetermined distance through said pipe spindle after the end portion has been severed from the pipe, and wherein the chuck spindle means is movable along an axis substantially perpendicular to said longitudinal axis for carrying said bearing

race to the plane grinding wheel for plane grinding said end surface after said end portion has been severed from the pipe to produce said bearing race.

10. Apparatus as set forth in claim 9, wherein the outer surface grinding wheel is provided with means for dressing the inner surface grinding wheel.

11. Apparatus for producing bearing races from an elongated pipe of bearing steel, the apparatus comprising:

a pipe spindle for supporting the pipe for rotation about its longitudinal axis;

inner and outer surface grinding wheels for grinding the inner and outer surfaces, respectively, of an end portion of the pipe to the shapes of the inner and outer surfaces, respectively, of a bearing race; and

cutting means provided by one of the grinding wheels for severing the end portion from the pipe to produce a bearing race therefrom, wherein the inner and outer surface grinding wheels are supported for rotation about axes substantially parallel to the longitudinal axis of the pipe by inner and outer surface grinding wheel spindles, respectively, the inner surface grinding wheel spindle being movable along an axis substantially parallel to said longitudinal axis for enabling the inner surface grinding wheel to enter the end portion of said pipe and also being movable in a direction substantially perpendicular to said longitudinal axis for permitting the inner surface grinding wheel to be fed to the inner surface of said end portion, and the outer surface grinding wheel spindle being movable in a direction substantially perpendicular to said longitudinal axis for enabling the outer surface grinding wheel to be fed to the outer surface of said end portion, and wherein the inner surface grinding wheel spindle has a cover which faces the inner surface grinding wheel, and wherein the cover has an annular passage therein, means for carrying grinding fluid to the passage, and a plurality of ports through which grinding fluid in said annular passage can be injected onto the inner surface of the end portion of the pipe during inner surface grinding.

12. Apparatus for producing bearing races from an elongated pipe of bearing steel, the apparatus comprising:

means for supporting the pipe;

inner and outer surface grinding wheels for grinding the inner and outer surfaces, respectively, of an end portion of the pipe to the shapes of the inner and outer surfaces, respectively, of a bearing race, each of the grinding wheels having rough and finish grinding parts for simultaneously finish grinding and rough grinding said end portion and an adjacent portion, respectively, of the pipe; and

cutting means for severing the end portion from the pipe to produce a bearing race therefrom, said cutting means being provided by one of said grinding wheels.

13. Apparatus as set forth in claim 12, further comprising means for plane grinding the bearing race end surface which is formed by severing said end portion from the pipe to produce said bearing race.

14. Apparatus as set forth in claim 12, further comprising feeder means for moving the pipe a predetermined distance in the direction of its longitudinal axis after the end portion has been severed from the pipe.

15

15. Apparatus as set forth in claim 12, wherein the grinding wheels are formed-type grinding wheels, and wherein the apparatus further comprises means for dressing said grinding wheels.

16. Apparatus as set forth in claim 12, wherein the cutting means is provided by said outer surface grinding wheel.

17. Apparatus as set forth in claim 12, further comprising means for causing said end portion of the pipe

16

to be ground in succession by the rough grinding part of the outer surface grinding wheel, the rough grinding part of the inner surface grinding wheel, the finish grinding part of the outer surface grinding wheel, and the finish grinding part of the inner surface grinding wheel, and then for causing said end portion to be severed from the pipe by said cutting means.
